UNITED STATES PATENT OFFICE

2,583,827

ARTIST'S COLOR DISPENSER

Louis Francis, Miami, Fla., assignor to
J. D. Howard, Inc., Miami, Fla.

Application February 2, 1951, Serial No. 209,041

2 Claims. (Cl. 222—126)

1

This invention relates to a color dispenser for artists.

An object of this invention is to provide a dispensing cap or attachment for a collapsible tube of the type used by artists in the formation of color combinations so that an excess of color may be squeezed from the tube without waste.

Another object of this invention is to provide a device of this kind which will support the tube in inverted position so that the color can be easily removed from the device as needed. Where all of the color discharged from the tube has not been used, the remaining color can be kept soft and workable by turning the cap with the open end thereof uppermost and then filling the cap with oil or other liquid for preventing air contacting the color.

The container or cap includes an extension plate on one wall thereof which extends from the open end and said plate may be bent from a coplanar position to an angular position to thereby form a prop for tilting the container so that relatively fluid paste will not flow out of the container. The plate in its angular position may be used as a stop for engagement with an edge of a plane surface. This plate or flap may also be bent upwardly to serve as a closure for the container.

The container or cap herein disclosed is preferably formed out of material which will not corrode or oxidize under the action of the paste material, one form of such material being pure lead.

Another object of this invention is to provide a container wherein the extension plate serves as a lock for the container and tube when these elements are mounted in an artist's box so as to hold the tubes in parallel relation irrespective of the shifting of the box.

With the above and other objects in view, my invention consists in the arrangement, combination and details of construction disclosed in the drawings and specification, and then more particularly pointed out in the appended claims.

In the drawings:

Figure 1 is a detailed side elevation of a container attached to an artist's color tube.

Figure 2 is a plan view of the container.

Figure 3 is a sectional view taken on the line 3—3 of Figure 2.

Figure 4 is the fragmentary longitudinal section of the top wall of the container.

Figure 5 is a detailed side elevation partly broken away and in section of a modified form of this container.

Figure 6 is a detailed side elevation of the container shown in Figures 1, 2, and 3 with the ex-

2

tension plate bent downwardly to provide for tilting of the container.

Figure 7 is a detailed side elevation of the container showing the same with the extension plate in closed container sealing position.

Figure 8 is a detailed side elevation of the container on a tube with the container in a vertical position.

Figure 9 is a view similar to Figure 8 but showing the container and tube mounted in an artist's box at one edge of a pallet.

Figure 10 is a fragmentary plan view of the structure shown in Figure 9.

Referring to the drawings and first to Figures 1, 2, and 3 the numeral 15 designates generally a housing which is formed of upper and lower walls 16 and 17, respectively, opposite side walls 18 and a rear wall 19. The forward end of the housing 15 is open and the forward end of housing 15 is enlarged by bending the upper wall 16 upwardly on a curvature as indicated at 20. The opposite side walls 18 are also provided with enlarged forward ends, and the forward edges of the side walls 18 are upwardly and rearwardly inclined as indicated at 21.

An extension plate 22 extends forwardly from the bottom wall 17 and may be disposed in either a position coplanar with bottom wall 17 or be bent downwardly at substantially a right angle as shown in dotted lines in Figure 1 so that the downwardly bent extension may serve as a prop to hold the container 15 in a tilted position with the open forward end uppermost.

A collapsible color tube 23 having a threaded neck 24 is adapted to be threaded into an opening 25 which is formed in the upper wall 16 at a point closely adjacent the rear wall 19, in order to provide a means whereby collapsible tubes having different sizes of threaded necks may be secured to the top wall 16. This wall is formed with a pair of deeply cut or pressed circular grooves 26 which are concentric with the opening 25. Where a neck 24 is too large to be threaded into opening 25, this opening may be enlarged by using a knife or the like to cut into the nearest groove 26 to the outside diameter of the neck 24.

Referring now to Figure 5 there is disclosed a container 15a which is similar to a container 15 with the exception that the rear wall 19a is disposed at right angles to the top and bottom walls 16a and 17a respectively.

Referring to Figures 7 and 8, there is disclosed a slightly modified form of this invention wherein the extension plate 22b which extends from the bottom wall of the housing 15b is of sufficient

length to close the forward end of the housing 15b when plate 22b is bent upwardly and rearwardly as shown in Figure 7.

The opening 25 in the top wall 16 is so placed with respect to the rear end of the housing 15 that when the tube 23 is horizontally disposed the rear end 19 will be resting on the horizontal surface which is engaged by the tube 23.

Referring now to Figures 9 and 10 there is disclosed the manner in which the attached container for the color tube is mounted in the artist's box 27. This box 27 is provided with supporting means 28 for supporting the pallet 29 above the bottom wall 30, and the color tubes are normally loosely placed below the pallet 29.

Through the use of the attached containers 15 the color tubes 23 will be normally disposed in parallel relation within the box 27, and the extension plates 22 will extend upwardly and substantially abut against one edge of the pallet 27.

In the use and operation of this device the color tube 23 has the normal cap removed therefrom, and the threaded neck 24 is threaded into the top wall 16. The color is removed from the tube 23 by squeezing the latter so that the color material will be discharged into the container 15. The color material can be removed from the inside of the container 15 through the open forward end thereof by the pallet knife.

In the event the artist stops work for any reason for a relatively long period of time which might be sufficient to dry out the color material, the tube 23 may be horizontally disposed as shown in Figure 8, and an oil or other liquid may be poured into the mouth of the container. In this manner the color will be maintained soft.

Where the structure shown in Figures 7 and 8 is used, the unused color material may be kept soft by bending the extension plate 22b to a closed position over the forward end of the housing 15b.

The container herein disclosed is preferably formed out of such material as will not corrode or oxidize by contact with the color material, and as one example the container may be formed

out of pure lead. This device will provide a means whereby the artist will not unduly waste the color material in using such material, and the unused material may be kept in soft workable condition by pouring oil, water or other liquid into the container which is disposed in an upright position.

I claim:

1. A dispensing container for artist's color tubes comprising a housing having an open end and formed of upper and lower walls, opposite side walls, a rear wall, and an extension plate extending from said lower wall at the open end of the container, said container being formed of deformable non-resilient material having a characteristic such that said plate may be angularly bent in a plurality of directions to provide for holding said container in tilted position, or for closing the open end of the container.

2. A dispensing container for artist's color tubes comprising a housing having an open end and formed of upper and lower walls, opposite side walls, a rear wall and an extension plate extending from said bottom wall, said top wall being upwardly curved at the open end of the container to form a flared mouth, the forward edges of said side walls being upwardly and rearwardly inclined, said extension plate being of a deformable non-resilient material and bendable upwardly and rearwardly to a closed position against the forward edges of said side walls and said upper wall.

LOUIS FRANCIS.
